UNITED STATES PATENT OFFICE.

VINCEN P. McVOY, OF MOBILE, ALABAMA, ASSIGNOR OF ONE-HALF TO JOSEPH M. WALSH, OF MOBILE, ALABAMA.

BOTTLE-GUIDE FOR FILLING-MACHINES.

1,315,140.

Specification of Letters Patent.

Patented Sept. 2, 1919.

Application filed February 3, 1916. Serial No. 75,963.

To all whom it may concern:

Be it known that I, VINCEN P. McVOY, a citizen of the United States, residing at Mobile, in the county of Mobile and State 5 of Alabama, have invented certain new and useful Improvements in Bottle-Guides for Filling-Machines, of which the following is a specification.

This invention relates to certain new and 10 useful improvements in bottle guides for bottling machines and it has for its objects among others to provide a simple, cheap, efficient and durable bottle guide readily attachable to or usable in connection with 15 bottling machines of any well-known make.

It has for a further object to provide a bottle guide of few parts, those readily assembled and easily adjusted and by the use 20 of which bottles are prevented from being chipped, time is saved, as well as effecting a saving of syrup, syrup tubes and the carbonated water.

It has for a further object to provide a 25 guide embodying a spring which normally is inoperative, that is, does not serve any useful function when the bottles are coming in average lengths and uniform size, but automatically comes into play in case the bottles vary in length.

30 Other objects and advantages of the invention will hereinafter appear and the novel features thereof will be particularly pointed out in the appended claims.

The invention is clearly illustrated in 35 the accompanying drawings, which, with the numerals of reference marked thereon, form a part of this specification, and in which—

Figure 1 is a side elevation of my im- 40 proved bottle guide.

Fig. 2 is a substantially central longitudinal section through the same as applied to a bottle during ordinary use.

Fig. 3 is a similar view showing the relative position of parts when the guide is employed on a longer-necked bottle.

Fig. 4 is a cross section on the line 4—4 of Fig. 1, looking in the direction of the arrow.

50 Fig. 5 is a perspective view of the gage employed for determining the proper adjustment of the syrup point while installing the guide.

Like numerals of reference indicate like 55 parts throughout the several views.

As is well-known to all familiar with the

art of bottling, a long bottle is often receiving the syrup while a short bottle is receiving the carbonated water and the crown. Naturally, this would cause the machine to drop the guide further down than normal which results in breaking the bottle receiving the syrup or causing other damage to the syrup valve. By the employment of a guide that is constructed to yield to compensate for the difference in the height of bottles, I avoid breakage of the bottle and damage to the syrup valve, and also provide a guide well adapted for the varying lengths of bottles and one that will compensate for or take care of the average 60 troubles of the bottler.

My improved guide, possessing the above advantages, is constructed as follows:—

1 is the bell member or portion terminating in the outwardly extended flange 2, the inner surface of which is tapered at 3, the taper being on an incline of substantially 45°. The outer periphery of this flange 65 may or may not be provided with an elastic or yielding ring 4, as shown in Figs. 2 and 3. This yielding ring, however, has been found in many instances desirable as it prevents chipping or damage to the bottles in 70 handling and in placing them in position, 75 as will be readily understood.

The upper end of this bell portion 1 is provided with an interior shoulder 5, as seen clearly in Fig. 3.

6 is a sleeve fitted to slide within the bell member 1, the lower end thereof being tapered, as shown at 7, and adjacent said lower end provided exteriorly with a shoulder 8 adapted to coöperate with the shoulder 5 at the upper end of the bell 80 member, as seen in Fig. 2. This sleeve member is longitudinally slotted at preferably diametrically opposite points, as seen at 9, 9, for a material portion of its length and at its upper end provided with the inwardly extended thickened portions 10 which are provided with a longitudinal bore 11, as seen clearly in Fig. 4, for the passage 95 of the syrup tube 12 of ordinary construction, the latter being provided at its point 100 with the delivery openings 13 and with a screw-threaded portion 14, whereby it is attached to the bottling machine in the usual way. No claim however, is made in 105 this application to this syrup tube or its attaching means.

The sleeve 6 is provided exteriorly near

its outer end with an annular ring or the like 15 and surrounding this sleeve between this ring and the adjacent end of the bell member 1 is a spring 16.

- 5 In assembling the parts, the sleeve 6 is inserted within the bell member through the lower end thereof, the spring is then applied around the sleeve from the top end, and the ring 15 is then placed in position
- 10 over the top end of the sleeve; in order to prevent displacement of the ring 15, I then punch out from the material, by means applied interiorly of the sleeve, a plurality of projections 17, as seen in Figs. 1 and 4,
- 15 which form abutments to limit the upward movement of the ring.

In applying the guide to the bottling machine, it is slipped up over the syrup tube 12 in the usual manner, the tube being received

- 20 within the bore 11 of the thickened portions 10 and the split end of the sleeve is fastened to the syrup tube by means of screws or the like 18, the heads of which are seated in depressions or cavities 19 in the one portion of
- 25 the sleeve engaging screw-threaded openings in the opposite member and by tightening up these screws the split members of the sleeve form a clamp, as will be readily understood upon reference to Figs. 2 and 4.
- 30 By loosening these screws, the guide may be adjusted to any desired position along the length of the syrup tube. In order that the split ends of the sleeve may thus be loosened and tightened, the collar 15 is loose upon
- 35 the sleeve, being held against upward displacement by the projections 17 and, of course, held against undue movement in the other direction by the tension of the spring 16, yet this collar is capable of freedom of
- 40 movement within certain limits upon the sleeve.

In use, the parts are in the relative positions in which they are shown in Fig. 2. The guide is placed over the mouth of the

- 45 bottle in the usual way and the operation continues under normal conditions. Now, should the bottle which is receiving its crown be broken, or should it happen to be a shorter bottle than the bottle which is receiving the syrup, under ordinary conditions the bottle receiving the syrup also would be broken, but by the employment of my improved bottle guide this cannot happen for should these conditions arise the bell member 1 of my guide would simply be moved upward when it contacts with the bulge of the bottle, as seen in Fig. 3, the spring then compressed, thus allowing of the bottle receiving its syrup without any danger of
- 55 breakage of the bottle or injury to the syrup tube or loss of syrup. The sleeve and bell members are so arranged as to at all times move coaxially so that the bell member cannot fail to move upward, but will not be
- 60 moved by contact of the neck of the bottle

with the rim or flange 2 upon one side of the axial center of the sleeve. After the syrup has been introduced into the bottle and pressure of the bottle on the bell member removed, the spring returns the parts from the position in which they are seen in Fig. 3 to that shown in Fig. 1, ready for another operation. The guide continues to operate without relative movement of the parts until similar conditions again arise when a like

70 75

operation takes place.

In Fig. 5 I have shown a gage member 20 comprising a strip adapted to span the mouth of the bell member and having a projection 21 adapted for contact with the end 80 of the syrup tube to determine the proper adjustment of the said tube before application of the guide to the bottling machine.

From the foregoing, it will be seen that I have devised an efficient form of bottle guide 85 capable of manufacture at small cost and adapted to serve the purpose for which it is intended without attention on the part of the operator, and while the structural embodiment of the device as hereinbefore disclosed is what I at the present time consider preferable, it is evident that the same is subject to changes, variations and modifications in detail without departing from the spirit of the invention or sacrificing any of its advantages. I, therefore, do not intend to limit myself to the precise construction and arrangement of parts, etc., as herein shown and described, but reserve the right to make such variations and modifications as come 95 100 properly within the scope of the appended claims.

What is claimed as new is:—

1. A bottle guide comprising a bottle-engaging member, a sleeve telescopically connected therewith, a ring surrounding the sleeve, a spring interposed between said ring and the adjacent end of the bottle-engaging member and holding them distended under normal operative filling conditions, and means limiting the upward movement of said ring.

2. A bottle guide comprising a bottle-engaging member, a sleeve telescopically connected therewith, a ring surrounding the sleeve, a spring interposed between said ring and the adjacent end of the bottle-engaging member and holding them distended under normal operative filling conditions, means limiting the upward movement of said ring, 110 and means on the sleeve constituting a clamp for clamping the holder to a syrup tube.

3. A bottle guide comprising a bottle-engaging member, a sleeve telescopically received therein, a ring loosely embracing said sleeve, a spring surrounding the sleeve and held between said ring and the adjacent end of the bottle-engaging member and holding the said member and sleeve in fixed distended relation during the normal operative fill-

125 130

ing conditions, and means on the sleeve forming abutments for said ring to limit its upward movement.

4. A bottle guide comprising a bottle-engaging member, a sleeve telescopically received therein, a ring loosely embracing said sleeve, a spring surrounding the sleeve and held between said ring and the adjacent end of the bottle-engaging means and holding 10 said sleeve and member distended during normal filling operations, means on the sleeve forming abutments for said ring to limit its upward movement and means on the sleeve constituting a clamp for securing the 15 guide to a syrup tube.
5. A bottle guide comprising a bottle-engaging member, a sleeve telescopically received therein and held in fixed relation thereto when in operative filling position 20 and longitudinally slitted yielding means normally holding said member and sleeve in their relatively distended position, and means for clamping the slitted ends upon a syrup tube.
- 25 6. A bottle guide comprising a bottle-engaging member, a sleeve telescopically engaged therein and held in fixed relation thereto when in operative filling position and longitudinally slitted, means for preventing separation of the sleeve and bottle-engaging member, and means for clamping the guide to a syrup tube.
- 30

7. A bottle guide comprising a bottle-engaging member, a sleeve telescopically received therein and held in fixed relation 35 thereto when in operative filling position and longitudinally slitted and provided with inwardly extended thickened portions, yielding means normally holding said member and sleeve in their relatively distended position, and means engaging said thickened portions to clamp the guide upon a syrup tube.

8. A bell-shaped bottle guide comprising a bottle-engaging member adapted to loosely 45 receive the neck, and to engage the bulge of a bottle and having an internal shoulder, a tubular member fitted to slide within the bottle-engaging member and having a co-operating shoulder, a normally inoperative 50 spring interposed between said members to normally hold the latter in their distended position when in operative filling position, said members arranged for coaxial movement when a bottle of more than 55 the average length is used and means for clamping the tubular member to a syrup tube.

In testimony whereof I affix my signature in presence of two witnesses.

VINCEN P. McVOY.
